FOLDABLE COMB

Willie Lee Morrow, 4167-9 Market St.,
San Diego, Calif. 92106

Filed Nov. 1, 1971, Ser. No. 194,794

Term of patent 14 years

Int. Cl. D28—03

U.S. Cl. D86—8

Fig. 1

Fig. 2

Fig. 3

Fig. 4

Fig. 5

Fig. 6

FIG. 1 is a side elevation view of a foldable comb, showing my new design;

FIG. 2 is a top plan view thereof;

FIG. 3 is a bottom plan view thereof;

FIG. 4 is a side elevation view of the comb in folded position and from the side opposite to that shown in FIG. 1;

FIG. 5 is an end elevation view as taken from the right hand end of FIG. 4; and

FIG. 6 is an end elevation view as taken from the left hand end of FIG. 1.

I claim:

The ornamental design for a foldable comb, as shown.
